UNIVERSAL VALVE FOR AIR VENTILATION SYSTEM

James M. Dudley, 2220 Southside Blvd.,
Jacksonville, Fla. 32216

Filed Aug. 18, 1966, Ser. No. 3,530

Term of patent 14 years

(Cl. D62—1)

FIG.1

FIG.3

FIG.2

FIG.4

FIG.5

FIG. 1 is a front perspective view of the universal valve for air ventilation system, showing the valve plate in open position;

FIG. 2 is a rear perspective view thereof;

FIG. 3 is a side elevational view thereof, showing the valve plate in closed position;

FIG. 4 is a bottom plan view thereof; and

FIG. 5 is a top plan view thereof.

I claim:

The ornamental design for a universal valve for air ventilation system, substantially as shown as described.
